THE NORRIS PETERS CO., PHOTO-LITHO, WASHINGTON, D. C.

UNITED STATES PATENT OFFICE.

PHILIP VETTER, OF SPRINGFIELD, OHIO.

BAKE-OVEN.

SPECIFICATION forming part of Letters Patent No. 653,272, dated July 10, 1900.

Application filed October 4, 1899. Serial No. 732,453. (No model.)

To all whom it may concern:

Be it known that I, PHILIP VETTER, a citizen of the United States, residing at Springfield, in the county of Clark and State of Ohio, have invented certain new and useful Improvements in Bake-Ovens, of which the following is a specification, reference being had therein to the accompanying drawings.

This invention relates to certain new and useful improvements in baking-ovens.

The general object of this invention is to provide an oven in which the largest amount of heat generated shall be used and at the same time the oven maintain an even temperature throughout its entire area, and this is accomplished by providing flues separated from each other and forming the bottom of the oven, while the return-flue to the chimney is of such size that the heated gases are held in contact with the upper partition of the oven a sufficient length of time to thoroughly heat such partition.

My invention also relates to details of construction and arrangement hereinafter appearing and more particularly pointed out in the claims.

In the accompanying drawings, on which like reference letters and figures indicate corresponding parts, Figure 1 is an end elevation of my improved oven; Fig. 2, a partial sectional view on the line *xx* of Fig. 1, showing the sliding dampers for opening and closing the direct draft; Fig. 3, a horizontal sectional view on the line *yy* of Fig. 1 looking in the direction of the arrows; Fig. 4, a cross-sectional view on the line *zz* of Fig. 3; Fig. 5, a detail view of one of the dampers, together with its connections for operating it. Fig. 6 represents detail views of windows through which light is reflected into the oven; and Fig. 7, a detail view of the mica-holder for one of said windows, partly in section.

In baking bread quickly and economically the heat within the oven must be as nearly uniform as it is possible to get it, and at the same time the construction must be such that the largest number of heat units will be utilized in heating the oven. All this I have accomplished in a marked degree and am able to turn out very large bakings, while at the same time the cost of such bakings is mate-

rially lessened by the construction about to be described.

The letter A represents the fire-box, while the letter B represents the ash-box, the usual grate-surface C being employed for separating the two receptacles.

The letter D represents one of a number of flues which connect with the fire-box and which extend rearwardly and upwardly from the fire-box, as illustrated in Fig. 3. The walls E of these flues may be formed of fire-brick or any other suitable material. By referring to Figs. 1, 2, and 4 it will be observed that these flues D are separated from each other and that there is a space F between each of them which opens directly into the oven. The upper walls of the flues, as also the arch G of the fire-box, form the bottom of the oven, and inasmuch as the flues D are separated from each other the greatest amount of heat is radiated therefrom, since it may be radiated from three sides, and, besides this, there is no intermediate wall or partition for absorbing the heat between the flues and oven proper, H. It will be seen that the flues D open into the vertical flue I, such flue being closed by slide-dampers J, as seen in Figs. 2 and 3. Below the dampers and extending the entire length and width of the oven is formed a flue K. Thus when the dampers J are closed the heat passes from the vertical flue I into the horizontal flue K, immediately above the oven proper, and consequently the heat completely surrounds the oven on three sides. In order that the heat in the passage K may be somewhat retarded, so that the oven proper will take up all of the heat units possible for it to take up, I provide a return-flue L of smaller dimensions than the flue K, yet at the same time sufficiently large to give the required draft.

It will be observed that within the oven is formed a track M, upon which is mounted a truck O. The side rails of the truck are preferably formed of angle-iron P and are united by cross-bars Q, formed of T-iron, while upon the T-iron are placed slabs R, preferably formed of slate or other suitable material. It will be observed that in front of the oven I have provided an extension S of the track in the nature of a bracket. The end of this

bracket is upturned, as shown at T, to form a stop for the truck to limit its outward movement, as will presently appear.

Referring now to Fig. 1, it will be observed that the ash-box is provided with a door U and the fire-box with a door V, while to the right and left of the fire-door doors a are provided for cleaning the flues D, located on either side of the oven, the flues immediately in front being cleaned through the door V. A slide-door b is provided, which is adapted to close the opening leading into the oven proper. To the upper end of this door are connected ropes or cables c, which pass over pulleys d and are secured at their ends to a weight e. This weight is provided with an extension f, which is large enough to receive a foot of a person to press the weight downward, and consequently raise the slide-door b. It will be understood, of course, that the slide-door is mounted in guides g. In order that the weight e may be elevated to permit the door to close the opening of the oven proper, I provide a pulley h, over which passes a rope i, connected at one end to the weight e and at its other end carrying a stirrup j. By placing the foot of the operator in this stirrup the weight e may be readily elevated, thereby permitting the door b to descend to closing position. The truck O is supported at its inner end by the roller k and at its outer end by a roller l, mounted on the lower end of the leg m. This roller i is adapted to run on a track o, carried upon the floor of the room in which the oven is located or in any other convenient manner. As the truck is drawn outward after raising the door b the truck-rollers k are adapted to come in contact with the upturned ends T of the bracket S. When the truck is in this position, it will be understood that it is entirely outside of the oven proper, and consequently the door b may be lowered to entirely close the opening of such oven proper. From Fig. 1 it will be seen that the door b is cut out, as shown at p, to clear the truck-rails P, it being understood that there is no slab adjacent to the forward end of the truck, so that the door b may readily fit over the truck-rails and substantially close the entrance to the oven proper. Thus when the truck is removed ready for refilling the oven is not losing heat.

In order to more thoroughly heat the forward end of the oven proper, I provide up-flues q, as shown in dotted lines in Figs. 1 and 3. These flues connect with the fire-box A and conduct a portion of the heat directly about the forward end of the oven proper. In order to regulate the amount of heat passing up these flues, dampers r are provided, which are operated by the handles s. Opposite the flues K and L are doors t for the purpose of cleaning such flues. The sliding dampers J are operated by rods 2, such rods extending through the front partition and having their outer ends bent to form handles 3 for more readily operating them.

I will now refer to the manner in which the temperature in the oven proper is determined and also the manner in which the oven proper is lighted, so that the baker may determine whether the bread, &c., is sufficiently baked without the necessity of removing the truck to test the bread. By referring to Fig. 1 it will be observed that I have provided openings in the front plate, as shown at 4. A frame structure such as shown at 5 in Figs. 6 and 7 is adapted to be placed within the opening 4, and within the frame structure is fitted a sheet of mica or other suitable material which will permit light to pass into the oven and at the same time will prevent the heat from passing out. The frame structure 5, it will be observed, is set back on a ledge 6 and against a projection 7. The projection 7 acts as a stop for the frame 5, while the ledge 6 supports a light. (Not shown.) These two openings light the interior of the oven, so that the condition of the baking may be observed through the peek-hole 8, such peek-hole being covered with a sheet of mica 9, held in position by a plate 10, screwed or otherwise secured to the front of the oven, as shown at 11. Thus we have seen that with my improved construction I am enabled to use the greater portion of heat units by reason of the lower flues D being separated from each other and communicating directly with the oven proper itself, while at the same time the oven proper is practically surrounded with the hot products of combustion at all times. Not only this, but the outward draft of the products of combustion is so controlled that the largest proportion possible of the heat units is utilized for heating the oven proper instead of passing up the chimney. By referring to Figs. 1 and 3 it will be observed that I use a heat-gage such as shown at 12. This gage is of any ordinary or approved construction and is adapted to indicate the temperature of the interior of the oven proper.

Having thus fully described my invention, what I claim as new, and desire to secure by Letters Patent, is—

1. In a bake-oven, the combination with an oven proper, of a fire-box located immediately beneath the forward portion of said oven proper, flues adapted to connect with said fire-box having spaces between them, said flues also forming a portion of the bottom of said oven proper, means for conducting the heat around the rear end and over the top of said oven proper, means for conducting a portion of the products of combustion from the fire-box around the forward end of said oven proper, and a return-flue adapted to retard the products of combustion and hold them longer within the passages or flues surrounding the oven proper, whereby the oven will take up a larger number of heat units, all substantially as shown and described.

2. In an oven, the combination with an oven proper, of separated flues having spaces between them forming the bottom of said oven,

means for communicating with said separated flues to conduct the products of combustion about one end of said oven proper and another flue above said oven and parallel therewith, 5 a return-flue of smaller diameter than said latter flue and communicating therewith, substantially as shown and described.

3. In a bake-oven, the combination with an oven proper, adapted to extend from the forward end to near the rear end thereof, of a fire-box beneath said forward end and forming a portion of the bottom of said oven, flues for communicating with said fire-box, and separated from each other and having a space 10 between them and also forming a portion of the bottom of said oven, another flue communicating with said separated flues between the rear end of the oven proper and the outer

wall, a pair of flues above said oven proper, one of which communicates with said end flue 20 and conducts the products of combustion to the forward end of said oven proper immediately above it, while the other flue is of smaller area and is adapted to act as a return-flue for said products of combustion, and one or more 25 dampers located in said end flue adapted to open and close the passage therein, whereby a direct draft or indirect draft may be had, all substantially as shown and described.

In testimony whereof I affix my signature 30 in presence of two witnesses.

PHILIP VETTER.
